ELECTRIC DRY SHAVER

Irving Florman, New York, N. Y.

Application October 22, 1937, Serial No. 170,442

3 Claims. (Cl. 30—43)

This invention relates to electric dry shavers and more particularly it relates to an electric dry shaver which is shaped like the ordinary safety razor and which can be operated in the same manner as the ordinary safety razor but without the use of soap or the like.

Like a number of electric shavers now on the market, the shaver according to the present invention works on the clipper principle having as it does a stationary clipper plate provided with teeth and a movable clipper plate also having teeth and adapted to reciprocate with respect to stationary plate. When the plates which are disposed like the blade of a safety razor are drawn across the face whiskers will be directed between the teeth and will be sheared off.

Practically all of the manufacturers of electric dry shavers warn their customers not to be discouraged with the first results of use since it frequently takes several weeks and sometimes months before the new strokes and manipulations necessary can be mastered. With the present invention no practice is necessary since the device is operated with the same strokes and manipulations as are used with the ordinary safety razor.

The present invention is further unlike the electric shavers now on the market in that the stationary and movable clipper plates are disposed so as to be in full view at all times so that the operator can see at all times how the razor shaves with each stroke.

It should already be manifest that one object of the present invention is the provision of an electric dry shaver which can be operated in the same manner as the usual safety razor but without the need for soap or the like. Another object which is apparent is the provision of an electric dry shaver so designed that the operator can see how the razor shaves with each stroke.

Another object of the invention is to provide an electric dry shaver in which the moving clipper plate is not covered and is so arranged as to be easily replaced.

Still a further object is to provide a shaver in which the moving plate is narrower than the stationary plate and is disposed above the stationary plate.

Other objects will be apparent from the following description and accompanying drawings.

In the drawings:

Fig. 1 is an enlarged perspective view of one embodiment of the invention showing only the upper portion of the shaver to which the invention relates.

Fig. 2 is a similar view with the movable clipper plate elevated to show the manner in which the stationary plate is secured.

Fig. 3 is an enlarged perspective view of the same embodiment with both the stationary and movable plates removed and showing one of the spring guides.

Fig. 4 is an enlarged front elevation of the shaver shown in Figs. 1 to 3.

Fig. 5 is an enlarged side elevation.

Fig. 6 is a top plan view also enlarged.

Fig. 7 is an enlarged detail view of one manner of connecting the actuator to the moving plate, and

Fig. 8 is an enlarged side elevation of another embodiment utilizing movable and stationary clipper plates which are slightly curved in cross section.

15

The electric dry shaver illustrated in the drawings has a handle 2 which may be of hard rubber, "bakelite" or any suitable insulation material. The handle preferably should be comparatively small and narrow so as to simulate as closely as possible the size and shape of the handle of the ordinary safety razor. The handle houses a small electric motor (not shown) which may be of the type used in dry shavers and which is connected by suitable mechanism 20 to impart a limited reciprocatory movement to an actuator 4 which extends upwardly from a rectangular well in the upper end of the handle 2.

Formed as to fit in the well is a supporting member 6 of metal or the like. The member 6 may be die-cast or even stamped and, as shown, has channelled end portions 8 (see Figs. 1 and 5 for example), and top flange portions 10 which extend over the top surfaces of the handle 2 on each side of the rectangular well. The supporting member has a central opening 30 for the actuator 4.

The reference numerals 12, 12' indicate supporting posts of metal or other suitable material. 35 The bases of these supporting posts 12, 12' are preferably square in cross section and they are snugly disposed in the channelled end portions 8 of the supporting member 6 to which they are secured by suitable means such as by the screws 40 14 and 16.

The outer sides of the supporting posts 12, 12' are beveled inwardly towards their upper ends to permit an inward swinging motion of spring members generally indicated by the reference 45 numeral 18. These may be secured nearer the base of the supporting posts 12, 12' by the screws 16. The spring members 18 may be of one piece (not shown) or they may be comprised of a heavier upper piece 20 of non-spring 50 metal secured to a lower thin leaf spring piece 22. The purpose of the spring members, as will be more apparent later, is to aid the reciprocatory movement of the movable clipper plate.

The device utilizes a stationary metal clipper 55

plate 24 and a movable metal clipper plate 26, the latter being slightly narrower in width. Each of the plates is provided along its longitudinal edges with teeth 28, 28' so that when the movable plate blade is reciprocated longitudinally a clipping or shearing action between the teeth of the plates is effected.

The stationary plate 24 is mounted on the supporting posts 12, 12' by means of screws 30 as shown in Figs. 2 and 4 most clearly. The screws 30 are also used to hold the spring guides 32 in place, the inner ends of the latter being disposed between the stationary plate and the supporting posts when the device is assembled. One of these spring guides 32 is shown in perspective in Fig. 3. They have a rectangular opening through which the spring members 18 pass and their purpose is to limit the outward motion of the spring members. As shown in Fig. 2, for example, the ends of the stationary plate 24 have rectangular recesses 34 to permit greater movement of the spring member. The stationary plate 24 also has a central opening 36 through which the actuator 4 extends. The opening 36 is large enough to permit full reciprocatory movement of the actuator 4.

The movable plate 26 is disposed above the stationary plate 24. It is reciprocated longitudinally by the actuator 4 which may engage a recess formed in the under side of the movable plate. As shown in Fig. 7 the under side of the movable plate may be provided with a rectangular ridge 38, the actuator 4 engaging in the well bounded thereby.

The movable plate 26 is held against the stationary plate by the T-shaped upper ends of the spring members 18, the under edges of the cross portions of which engage the upper surfaces of the movable plate adjacent small rectangular cut-outs 40 in the ends of the plate (Fig. 2). The vertical or upright portion of the T-shaped spring members 18 engage in these cut-outs. Small up-turned portions 42 adjacent the cut-outs 40 (also see Fig. 2) aid in keeping the movable plate in place on the stationary plate.

From the above description it is probably now apparent that the device operates in the following manner. The actuator 4 driven by the motor in the handle reciprocates the movable plate 26 along its longitudinal axis. As the movable plate moves first in one direction and then in the other, it presses the spring members 18 outwardly. The spring members are tensioned so that they will aid in returning the plate to neutral position. The inward and outward movement of the spring members is limited by the spring guides 32. While the spring members facilitate the smooth running of the device and are thus preferred, they may be dispensed with. A construction in which they are not present is within the bounds of the invention.

As shown in Fig. 8, the stationary and movable plates may be slightly curved in cross section. In this figure these plates are indicated respectively by reference numerals 24' and 26'. Aside from this difference, the arrangement shown in Fig. 8 is similar to that illustrated in the other figures. The movable plate may have a slightly greater cross sectional curvature as this aids in keeping the teeth of the plates in contacting position when the movable plate is held down by the T-shaped spring members.

Naturally a reciprocatory movement of the movable plate may be effected by means other

than the actuator 4. For example, the reciprocatory movement may be effected by having a rotatable shaft on the end of which a pin is eccentrically disposed. This pin engages a slot or recess in the movable plate.

The device illustrated and described is of simple construction. Since the movable plate is disposed above the stationary plate and is not covered by a protecting member, it may be easily replaced. At the same time it is possible for the operator to use the device by employing the same strokes as are customary with an ordinary safety razor. The operator can see at all times how the shaving is progressing and obtain an excellent shave without previous practice.

It is obvious that modifications of the invention disclosed can be made without departing from the inventive concept, and I do not intend to be limited except as indicated in the following claims.

I claim:

1. In an electric dry shaver, an elongated handle housing an electric motor, said handle having a rectangular well in one end thereof, a supporting base disposed in the well and having end portions of channel shape, a pair of supporting posts disposed in said channel-shaped portions and extending from said end of the handle, a stationary clipper plate rigidly secured to the ends of said posts, a movable plate disposed above the stationary plate, both of said plates having teeth along corresponding edges which teeth at least in part overlap, and means connecting the motor with the movable blade to impart a reciprocatory movement to the movable blade to effect a shearing action between the teeth on the plates.

2. In an electric dry shaver, an elongated handle housing an electric motor, said handle having a rectangular well in one end thereof, a supporting base disposed in the well and having end portions of channel shape, a pair of supporting posts disposed in said channel portions and extending from said end of the handle, a stationary clipper plate rigidly secured to the ends of said posts, a movable plate disposed above the stationary plate, both of said plates having teeth along corresponding edges which teeth at least in part overlap, means connecting the motor with the movable plate to impart a reciprocatory movement to the movable plate to effect a shearing action between the teeth on the plates, and means for retaining the movable plate in overlying movable position with respect to the stationary plate.

3. In an electric dry shaver, an elongated handle housing an electric motor, said handle having a rectangular well in one end thereof, a supporting base disposed in the well and having end portions of channel shape, a pair of supporting posts disposed in said channel portions and extending from said end of the handle, a stationary clipper plate rigidly secured to the ends of said posts, a movable plate disposed above the stationary plate, both of said plates having teeth along corresponding edges which teeth at least in part overlap, means connecting the motor with the movable plate to impart a reciprocatory movement to the movable plate to effect a shearing action between the teeth on the plates, and means for aiding the reciprocatory movement of the movable plate while holding it in position against the upper surface of the stationary plate.
